UNITED STATES PATENT OFFICE.

ROBERT M. SEARLE, OF ROCHESTER, NEW YORK.

SUPPORTING MEANS FOR GAS-RETORT SPOUTS.

Application filed November 11, 1922. Serial No. 600,215.

To all whom it may concern:

Be it known that I, ROBERT M. SEARLE, a citizen of the United States, and a resident of Rochester, in the county of Monroe and State of New York, have invented certain new and useful Improvements in Supporting Means for Gas-Retort Spouts, of which the following is a specification.

The present invention relates to supporting means for gas retort spouts. An object of this invention is to provide means for counter-balancing the projecting spout portion of the retort so as to remove the weight of the projecting spout portion and closure from the bolts or securing means so that when the retort becomes hot the weight of the projecting spout portion and closure will not be imposed upon the bolts to cause the disconnection of the projecting spout portion.

To these and other ends, the invention consists of certain parts and combinations of parts, all of which will be hereinafter described: the novel features being pointed out in the appended claims.

In the drawings:

Fig. 1 is a front view of a gas furnace constructed in accordance with this invention;

Fig. 2 is a side view; and

Fig. 3 is a top plan view.

Referring more particularly to the drawings, 1 indicates the furnace which has any suitable number of retorts mounted thereon. In this illustrated embodiment, three retorts are shown. Each of these retorts has a body portion, not illustrated, lying within the furnace proper and a projecting spout portion 2 secured to the furnace in a known manner by bolts 3. This projecting spout portion carries a closure or door 4 through which access to the interior of the retort may be obtained.

The feature of this invention is the counter-balancing of the projecting spout portion 2 of the retort so that the weight of the said projecting spout portion and the closure 4 is removed from the securing means or bolts 3 in order that the latter will merely act to hold the projecting spout portion 2 and

closure 4 in position. Any suitable counter-balancing means may be employed. In this instance, where there are shown three retorts, three levers 5 are employed pivoted between their ends upon a common shaft 6 and each having on one side of its pivot a weight 7 adjustable on said lever. Preferably the levers are disposed above the furnace on uprights 8 which support the shaft 6 from the top wall of the furnace. Each lever 5 has at the end opposite the weight a flexible connection with one of the projecting spout portions 2. In this instance, this flexible connection is in the form of a steel cable made in two loops 9 and 10, the loop 9 being passed over the lever 5 and the loop 10 being passed under one of the projecting spout portions 2 so that it lies also on opposite sides of said projecting spout portion and also on opposite sides of those projecting spout portions 2 above the projecting spout portion sustained by the flexible connection.

From the foregoing it will be seen that there has been provided a gas furnace in which the projecting spout portions of the retorts are counter-balanced so as to remove from the securing means of said projecting spout portions the weight of said projecting spout portions and their closures in order that the projecting spout portions will not become detached from the furnace when the bolts are heated.

What I claim as my invention and desire to secure by Letters Patent is:

1. The combination with a retort having a spout portion projecting from a furnace, bolts securing said spout portion in position on the furnace, and a closure for said projecting spout portion, of counter-balancing means for said projecting spout portion and closure.

2. The combination with a retort having a spout portion projecting from a furnace, bolts securing said spout portion in position on the furnace, and a closure for said projecting spout portion, of counter-balancing means for said projecting spout portion and closure embodying a lever, a weight on one side of the pivot of the lever, and a flexible

connection between said lever and the projecting spout portion.

3. The combination with a retort having a spout portion projecting from a furnace, bolts securing said spout portion in position on the furnace, and a closure for said projecting spout portion, of counter-balancing means for said projecting spout portion and

closure embodying a lever, a weight on one side of the pivot of the lever, and a flexible ¹⁰ connection between said lever and the projecting spout portion in the form of a loop passed beneath and on opposite sides of the projecting spout portion.

ROBERT M. SEARLE.
